UNITED STATES PATENT OFFICE.

ZEBULON E. BARKALOW, OF READING, PENNSYLVANIA.

DESIGN FOR A CHARGING-BLOCK.

SPECIFICATION forming part of Design No. 33,038, dated July 31, 1900.

Application filed June 27, 1900. Serial No. 21,849. Term of patent 14 years.

To all whom it may concern:

Be it known that I, ZEBULON E. BARKALOW, a citizen of the United States, residing in Reading, Pennsylvania, have invented a new and original Design for a Charging-Block, of which the following is a specification.

My design is fully shown in the accompanying drawings, in which—

Figure 1 represents a face view of the block;

Fig. 2, a section of the same on the line *a a*, Fig. 1; and Fig. 3 a section on the line *b b*, Fig. 1.

The block is of triangular outline and has opposite faces curved throughout their entire extent and meeting at the comparatively-sharp median edge 2 of the block.

The block is thickest at the point 1 and

gradually diminishes in thickness from this point toward the edges and curves of the block.

Having thus described my invention, I claim and desire to secure by Letters Patent—

The design for a charging-block, substantially as described and as shown in the accompanying drawings.

In testimony whereof I have signed my name to this specification in the presence of two subscribing witnesses.

ZEBULON E. BARKALOW.

Witnesses:

F. E. BECHTOLD,
JOS. H. KLEIN.
